PULSE DEMODULATOR SYSTEM

Arnold M. Levine, Forest Hills, N. Y., assignor, by
mesne assignments, to Federal Telephone and
Radio Corporation, Clifton, N. J., a corporation
of Delaware

Application October 21, 1947, Serial No. 781,031

5 Claims. (Cl. 250—27)

1

This invention relates to pulse demodulation systems and more particularly to pulse translator or demodulator systems for the translation or demodulation of time displaced pulses into other forms.

In pulse communication systems of the type in which intelligence is transmitted by varying the time displacement of a series of pulses relative to a given timing position, various forms of circuits have been devised for selecting pulses corresponding to a single channel and for translating these selected pulses into other forms of energy. In previous types of translation the variable time displaced pulses are translated into pulses having amplitudes or time durations corresponding to the time displacements of the individual pulses. These variations may then be transformed by filtering into the original intelligence wave. In the translators for translating the pulses into variable time duration signals circuits have generally been provided utilizing multi-vibrators or trigger tube circuits which do not lend themselves to compact construction and which may be difficult to control at sufficient rapidity to provide a precise timing or duration of variable duration pulses.

It is an object of my invention to provide a pulse translator and/or demodulator for translating pulses of variable time displacement into pulses of variable time duration by providing a control circuit for shunting, in response to the time displaced pulses, corresponding substantially fixed given time duration pulses, to translate such fixed pulses into pulses having a duration corresponding to the time displacements of these time displaced pulses.

According to a feature of my invention pulses may be produced in response to a marker pulse, or by other means, having a substantially constant time duration, these pulses corresponding in number to the number of pulses of time displacement energy and overlying in time the position of these time displaced pulses. These constant time duration pulses and the time displaced pulses are applied conjointly to a circuit to provide a termination for the fixed pulses at some interval intermediate its normal duration to provide resultant pulses having time durations corresponding to the time displacement modulation of the received pulses.

In accordance with my invention the combination of the pulses may be effected in a gating tube which may serve at the same time as a selector for the pulses of a desired channel of a multiplex pulse system. The circuit for accomplish-

2

ing the results of my invention includes also subordinate features relating to the shaping of the given duration pulses for the purpose of securing the desired output results and the complete system will include filters for the reproduction of the original signal envelope.

More specifically the base wave or selector pulse derived from the received waves or produced locally is first passed through a circuit which by amplification and clipping will produce trains of rectangular pulses having a substantially constant time duration. These pulses are passed through a circuit to suitable shaping and filter apparatus. In shunt to the circuit passing these constant duration pulses is provided a gating tube, to the grid-cathode circuit of which may be applied the rectangular constant duration pulses. This tube normally is biased so that it will not pass the normal channel pulses in the absence of the application of this rectangular pulse to the grid. The channel pulses are also applied to the grid cathode circuit and the pulses which arrive coincident with the rectangular pulse will serve to render the tube conductive, cutting off the rectangular pulse at the time of application of the channel pulse.

The above-mentioned and other features and objects of this invention and the manner of attaining them will become more apparent and the invention itself will be best understood, by reference to the following description of an embodiment of the invention taken in conjunction with the drawing the single figure of which illustrates a preferred embodiment of my invention.

In the drawing a multichannel receiver is indicated at 1 from which the signals received on antenna 2 or from any suitable source are received and demodulated to provide pulse envelope output for the variable pulse wave. This wave is illustrated generally at the curve 3 and may constitute a double marker pulse 4 and separate channel pulses 5 and 6. The output wave from receiver 1 is applied to a marker or reference pulse selector and pulse shaper 7 which serves to select marker or reference pulse 4 and shape it to some desired form. The output pulses from shaper 7 are applied to a distributor 8 which may be in the form of a pulse delay line tapped at various time intervals corresponding with the separate timing channels of pulses 5, 6, etc. From the output of distributor 8 are shown tapping lines 9, 10 and 11 going to the separate channel selectors and demodulators. Since the selectors and demodulators for the various chan-

nels may be identical in form, only that for line 9 is illustrated in the drawing.

The output pulse on line 9 may have a shape indicated by wave 12 and is supplied over coupling resistors to the input circuit of tube 13. In the output circuit of tube 13 an inductance coil 14 is provided which serves effectively to steepen the leading and trailing edges of the pulse 12 in the output circuit. Tube 13 may serve as a clipper circuit to clip pulse 12 at the level indicated by dotted line 16 on the curve 12. A rectifier 15 may serve to clip pulse 12 to eliminate noise near the upper portion thereof. A second by-pass rectifier 17 is provided shunting coil 14 to remove any residual negative voltages which may result from the inductive action of coil 14. The output pulse from tube 13 is positive and takes a rectangular shape as indicated at 18. This pulse has a substantially constant time duration and in view of the operation of distributor 8 is properly timed with respect to the incoming channel pulse so that it will overlie the time position of a channel pulse such as 5 for example, regardless of its time displacement. The time duration of pulses 18 is not critical but should be chosen so as not to overlap the time period of any of the other channel pulses. This output pulse is applied over leads 19 directly to the grid-cathode circuit of a tube 20. The pulse is also passed through coupling condenser 21 directly to the anode output circuit of tube 20. Preferably the pulse as passed through coupling condenser 21 is previously subjected to a voltage divider action through the medium of condensers 22 and 23. Condenser 23 is made variable and is shunted by a resistor 24 so that the resulting pulse passed to condenser 21 may be controlled in shape. Adjustment of condenser 23 changes the slope of the top portion of the output pulse shown at 25 in accordance with the dotted line indications of 26 and 27 to correct distortion in the pulse or to compensate for distortion which may occur in succeeding circuits.

The output pulses from receiver 1 are also applied over line 28 to the grid cathode circuit of tube 20 over cathode resistor 29. In the absence of any applied channel pulses, pulses 25 would appear in the output circuit of tube 20 as trains of pulses of constant duration. However, upon coincidence of the selected channel 5 and the pulse 18 in the grid cathode circuit of tube 20, tube 20 is rendered conductive and the plate voltage therefore is caused to drop, serving to cut off or terminate pulses 25 at a time corresponding to the application of the pulse 5. A time constant circuit consisting of resistors 30 and a coupling condenser 31 in the output of tube 20 serves to elongate the negative voltage existing at the plate for a period corresponding to the maximum remaining time duration of pulses 25 to assure that the entire portion of the pulse occurring subsequently to the application of a channel pulse 5 is eliminated. Thus in the output of the circuit of tube 20 the resultant pulse will appear as indicated at 32. Pulse 32 is clipped at level 33 in a clipper-shaper circuit 34 to provide output pulses 35 having time duration depending upon the time of arrival of the channel pulse 5. Thus as the channel pulses 5 are displaced in time due to signal or intelligence modulation, the output pulses 35 will correspondingly vary in width or time duration. These variable time duration pulses 35 may then be applied to an audio filter 36 to remove the high frequency components and reproduce the original audio frequency wave. The

output waves from filter 36 may then be applied to any desired utilization circuit 37.

It will be understood that if it is desired further to transmit the wave as a variable pulse duration wave instead of a time displacement wave, the output pulse from clipper shaper 34 may be applied directly to such further transmission circuit.

While I have described above the principles of my invention in connection with specific apparatus, it is to be clearly understood that this description is made only by way of example and not as a limitation to the scope of my invention.

I claim:

1. A pulse receiver system for receiving a wave consisting of successive time displaced modulation channel pulses comprising means for producing a wave of negative pulses time displaced to correspond with the time displaced pulses and of a substantially rectangular form of substantially constant time duration, voltage divider means for selecting a predetermined portion of said rectangular pulses, an electron discharge tube having anode, cathode and grid electrodes having its anode circuit coupled to the output of said voltage divider means, a coupling circuit for applying each of said substantially rectangular pulses to the grid circuit of said electron discharge device, said electron discharge device being normally biased beyond cutoff and said rectangular pulse serving to reduce said bias but being insufficient in amplitude to render said tube conductive, a coupling circuit for applying said channel pulses to the grid cathode circuit of said tube whereby said tube will be rendered conductive upon simultaneous application of a channel pulse and a rectangular pulse, said rectangular pulse serving effectively to reduce said pulse from the output of the voltage divider to zero, and time constant circuit means in the output of said electron discharge device for insuring persistence of said cutoff condition for a period corresponding to the remaining time duration of said rectangular pulse.

2. A system for translating pulses of variable time displacement into pulses of time duration corresponding to the time displacement of the individual pulses comprising means for providing pulses of a given time duration and corresponding in number to and overlying in time position each of said pulses of variable time displacement, a transmission path for normally passing said constant duration pulses, a normally inoperative shunting circuit coupled to said transmission path, said shunting circuit having an electron discharging device having an anode circuit coupled to said transmission path to shunt said path upon conduction of said device and an input grid-cathode circuit to which are simultaneously applied said constant duration pulses and said time displaced pulses to render said electron discharge device conductive upon coincidence of such pulses and thereby terminate each of said given duration pulses in accordance with the time position of the corresponding time displaced pulse.

3. A system according to claim 2 wherein said shunting circuit further includes a time constant circuit having a time constant at least as great as the remaining time duration of said given duration pulse to assure that the entire portion of the constant duration pulse, occurring subsequently to the application of the variable time displaced pulse, is eliminated.

4. A system according to claim 2 wherein said transmission path further includes a voltage divider in advance of said electron discharge device

and coupled to the anode circuit thereof, whereby only such amplitude portion of each of said given time duration pulses is passed by said voltage divider that only when applied to said electron discharge device simultaneously with the application of a variable time displaced pulse, will render said electron discharge device conductive.

5. A system according to claim 4 wherein said voltage divider includes a variable condenser and a shunt resistor to control the shape of said given time duration pulses and compensate for distortion in the said pulse.
